UNITED STATES PATENT OFFICE.

FREDERICK W. McGAW, OF MOORES MILLS, NEW BRUNSWICK, CANADA.

INCENDIARY EXPLOSIVE SHELL.

1,287,372.

Specification of Letters Patent. Patented Dec. 10, 1918.

Application filed March 18, 1918. Serial No. 222,175.

To all whom it may concern:

Be it known that I, FREDERICK W. McGAW, a subject of the King of England, residing at Moores Mills, in the Province of New Brunswick, Dominion of Canada, have invented certain new and useful Improvements in Incendiary Explosive Shells, of which the following is a specification, reference being had to the accompanying drawings.

This invention relates to explosive shells, and more particularly to incendiary explosive shells.

The general object of the invention is the provision of a shell of this character designed to contain a bursting charge of high explosive, a charge of highly inflammable liquid, and a detonating or firing pin arranged to explode both of said charges.

20 A further object is to construct the shell with a body and a head which, when the bursting charge is exploded, will be separated, said detachable body and head permitting the ready placing of the bursting charge and the inflammable charge within the shell of the casing.

25 A further object is to provide improved means of preventing the accidental detonation of the shell so as to render the shell entirely safe to handle.

Other objects will appear in the course of the following description.

30 My invention is illustrated in the accompanying drawings, wherein:

35 Figure 1 is a longitudinal vertical sectional view of a shell constructed in accordance with my invention;

40 Fig. 2 is an elevation of the shell illustrated in Fig. 1; and

Fig. 3 is a section on the line 3—3 of Fig. 1.

45 Referring to these drawings, 10 designates the head of the shell, which is conoidal in form and may be of any suitable material or thickness, the interior of this head being hollow to provide a chamber 11 within the head, this chamber being connected to the point of the shell by means of a bore 12 having a flaring outer end. The butt of the head 10 is reduced in diameter and interiorly and exteriorly screw-threaded as at 13. The body of the shell, which may be

made of thinner metal than the head and which is detachably connected thereto, is designated 14. This body is cylindrical in form and has screw-threaded engagement at its ends with the exterior screw-threads on the butt of the shell. Disposed within the rear end of the body is a sleeve 15 having a rearwardly tapering chamber normally closed by a plug 16. This gives a proper balance to the shell and gives a sufficient thickness to the rear end of the shell so that it may receive the impact of the exploding gases in the gun. A cap piece 17 is disposed over the plug 16 and the rear end of the shell, the margins of the cap piece being spun or bent down around the butt end of the body 14, as at 18.

55 Disposed within the bore 12 is a firing pin 19 having a rearwardly tapering head 20 disposed within the firing end of the bore 12. The shank of the firing pin fits the bore 12 and rearward of the bore is reduced and is surrounded by a coiled compression 75 spring 21 bearing against a spider 22 disposed within the chamber 11 and engaged in any suitable manner with the walls of the chamber. This spring 21 holds the firing pin projected. Having screw-threaded engagement with the interior screw-threads at 60 the butt end of the shell is a plate or plug 23 in which is disposed a second firing pin 24.

65 At a distance from the plug 18 the interior of the body or casing 14 is provided with an annular flange 25 and resting upon this flange are a plurality of annular wads 26. The outermost wads are made of paper and felt, but the middle wad is of relatively 70 hard material. These wads 26 define a rearward chamber and a forward chamber. The rearward chamber is filled with high explosive 27 while the forward chamber, which is defined between the wads and the 75 butt end of the head 10 is designed to support a plurality of frangible receptacles 28 containing highly inflammable liquids.

80 Surrounding these frangible receptacles which may be in the form of bottles of thin 100 glass is gun cotton or nitro cellulose, which is designated 29. This gun cotton serves not only as an explosive but serves as a packing surrounding the several receptacles

28 and preventing them being broken through accidental jar. Extending centrally through the mass of gun cotton 29 and centrally with relation to the several 5 receptacles 28 is a tube 30 which may be made of any suitable material and may contain gun powder or other explosive. This tube at its upper end rests upon a plate 31 in turn resting upon flanges 32 and the upper end of the tube is provided with a primer or detonating cap 33, while the lower end of the tube is closed by a plug of wadding 34. The detonating cap 33 is disposed immediately beneath the small firing pin 10 15 24 and this in turn is disposed immediately behind the firing pin 19.

It will thus be obvious that when the point of the shell strikes the objective, the firing pin will be forced inward against the small firing pin 24 and this will be forced inward against the detonating cap exploding the gun powder or other explosive in the tube 30. This explosion will cause the explosion of the high explosive 27 and also 25 of the gun cotton. The relatively thin walls of the body 14 will be blown apart, the frangible receptacles 28 will be broken and the inflammable liquid carried therein will be set on fire and thrown in all directions. 30 The case or body will separate from the head upon this explosion while the head is forced into the objective and the shell case is torn into fragments which will be cast in all directions. The shell casing is preferably 35 provided with a plurality of circumferentially extending bands 35, these bands being rifled and acting to reduce friction when the shell is within the gun.

For the purpose of preventing accidental 40 detonation of the shell when it is being handled or transported, I provide a protector. This comprises a plate 36 formed to provide a seat 37 for the point of the shell and having a plurality of longitudinally extending members 38 which at their extremities rest upon the shell band 35 which is adjacent the junction between the head and the body of the shell. Means may be provided for detachably engaging these members 38 with the body of the shell or with the shell band. This device prevents absolutely any accidental projection of the firing pin against the detonating cap so that the shell may be safely handled, without 55 any chance of explosion.

An incendiary shell of the character which I have illustrated is particularly useful for bombarding tanks containing inflammable liquids or gases or for bombarding ammunition dumps or munition magazines or factories. It may be also used very effectively for bombarding trenches, as fire is more feared than any other destructive agent. It will be obvious, of course, that this shell

may be of any desired size to fit any desired 65 caliber of gun and that it may be made very cheaply.

Having described my invention what I claim is:

1. A shell of the character described comprising a conoidal hollow relatively thick head, a hollow body of relatively thin material having screw-threaded engagement with the head, wadding disposed within the body and separating it into two compartments, a plate mounted within the body and extending across the butt end of the head, a tube containing explosive material carried by said plate and extending through the wadding, a primer mounted upon the forward end of the tube, explosive material carried in the rear compartment, a plurality of frangible receptacles disposed in the forward compartment and separated from each other by a packing of highly explosive material, a plug detachably engaged with the rear end of the head and having a firing pin coacting with the primer, and a firing pin mounted in the head and extending to the point thereof coacting with the first named firing pin, and a spring urging said last named firing pin outward away from the first named firing pin.

2. A shell of the character described comprising a relatively thick head and a hollow relatively thin tubular body, the rear end of the body being provided with a relatively thick sleeve, a plug fitting in the rear end of the sleeve, wadding forming a partition separating the body of the shell into two compartments, a tube containing explosive material extending through the center of the forwardmost compartment and into the rearmost compartment and through said wadding, and provided with a primer at its forward end, frangible receptacles containing inflammable fluids and disposed within the forward compartment concentrically to the tube, a packing of explosive material disposed within the body and separating the frangible receptacles from each other and from the body, and means carried in the head of the shell for detonating the explosive material in the tube.

3. A shell of the character described comprising a relatively thick head and a hollow relatively thin tubular body, the rear end of the body being provided with a relatively thick sleeve, a plug fitting in the rear end of the sleeve, wadding forming a partition separating the body of the shell into two compartments, a tube containing explosive material extending through the center of the forwardmost compartment and into the rearmost compartment and through said wadding, and provided with a primer at its forward end, frangible receptacles containing inflammable fluids and disposed within the

forward compartment concentrically to the tube, a packing of explosive material disposed within the body and separating the frangible receptacles from each other and 5 from the body, means carried in the head of the shell for detonating the explosive material in the tube, and a detachable protector operatively supported upon the body and having a member extending across the

apex of the shell in spaced relation thereto 10 and preventing the accidental detonation of the shell.

In testimony whereof I hereunto affix my signature in the presence of two witnesses.

FREDERICK W. McGAW.
